UNITED STATES PATENT OFFICE.

PHILIP T. DODGE, OF NEW YORK, N. Y., ASSIGNOR TO THE MERGENTHALER LINOTYPE COMPANY, OF NEW YORK.

LINOTYPE-MACHINE.

SPECIFICATION forming part of Letters Patent No. 576,397, dated February 2, 1897.

Application filed September 14, 1896. Serial No. 605,725. (No model.)

To all whom it may concern:

Be it known that I, PHILIP T. DODGE, of New York city, county of New York, and State of New York, have invented a new and useful Improvement in Linotype-Machines, of which the following is a specification.

In linotype-machines, such, for example, as that represented in Letters Patent to O. Mergenthaler, No. 436,532, the linotypes or slugs are cast in a slotted metal mold, the molten metal being delivered into the mold through a series of small openings in the mouth of the melting-pot, which is arranged to close for the time being tightly against the back of the mold. It is the common practice to change the length of the mold or to substitute a mold of one length for another of different length, in order to vary the length of the slug produced. When a short mold is used, there are obviously a number of delivery-openings in the pot-mouth beyond the limits of the mold-slot which are not used for the delivery of metal. In practice it has been found advisable to temporarily fill these idle holes with cement or other similar material or to remove the mouthpiece and substitute another having a row of delivery-openings equal in length to the mold.

The object of my invention is to avoid the delay, trouble, and expense incident to such operations and to provide a mouthpiece in which any desired number of the delivery-openings, commencing at one end, may be closed, according to the length of the mold employed. To this end I combine with the mouth of the pot a movable strip or bar adapted to cover and close the openings. This bar may be arranged to slide endwise into a groove within the mouthpiece, or when the mouthpiece is removable, as usual, a groove may be formed in the face and the closing-strip laid removably therein, so that it may be adjustable to one position or another, as demanded.

Figure 1 represents a perspective view of the pot provided with my improvement. Fig. 2 is a perspective view of the inner face of the mouthpiece detached and provided with my improvement. Fig. 3 is a vertical cross-section through the mouth of the pot in a fore-and-aft direction.

A represents the body of the pot, in which the metal is melted and in which there is mounted a pump-plunger for the purpose of delivering the molten metal through the 55 mouthpiece into the mold, as usual.

B represents the mouthpiece, having a flat face to fit against the rear side of the mold and having a series of openings c, through which the metal is ejected. This mouthpiece may be fastened permanently in position, or it may be removably secured, as usual. In its rear face I form, as shown in Fig. 2, a longitudinal groove d, extending across the inner ends of the delivery-openings, and into this groove I lay or slide a covering-strip e, adapted to fit snugly therein and to cover and close a number of the openings. This strip may be made of considerable length and adapted to move endwise to close a greater or a less number of the openings, according to the length of the mold to be employed, or a separate strip of appropriate length may be provided for each length of mold and laid in the groove from 65 the rear, as shown in Fig. 2. The covering or closing strip may be of dovetail or of rectangular form in cross-section. One of rectangular section is shown in Fig. 3. It will be held securely in place between the rear 70 face of the mouthpiece and the front of the mold proper.

The essence of my invention lies in combining with the pot-mouth adapted to deliver molten metal from a certain portion of 85 its width the adjustable covering or closing device to prevent the escape of metal from a portion of said width. In some cases pot-mouths are made with a continuous slit for the delivery of the metal instead of a series 90 of holes, and it is obvious that my improvement is applicable to pots in both forms.

Having thus described my invention, what I claim is—

1. In a linotype-machine, a melting-pot 95 having a delivery-mouth in combination with an adjustable metallic device closing said mouth for a portion of its width.
2. In a linotype-machine and in combination with the melting-pot having a delivery-mouth, the adjustable closing device e, substantially as described.

3. In a linotype-machine a melting-pot and a removable perforated mouthpiece therefor, in combination with a movable closing device, *e*, inserted between the mouth-piece and the pot proper, substantially as shown.

In testimony whereof I hereunto set my

hand this 1st day of September, 1896, in the presence of two attesting witnesses.

PHILIP T. DODGE.
